UNITED STATES PATENT OFFICE

JOHN STERLING GULLBORG, OF CHICAGO, ILLINOIS, ASSIGNOR TO ALEMITE DIE CASTING & MFG. CO., OF WOODSTOCK, ILLINOIS, A CORPORATION OF DELAWARE

DESIGN FOR A HANDLE FOR AUTOMOBILE WINDOW LIFTER OR THE LIKE

Application filed September 11, 1930. Serial No. 36,936. Term of patent 3½ years.

To all whom it may concern:

Be it known that I, JOHN STERLING GULLBORG, a citizen of the United States, residing at Chicago, in the county of Cook and State of Illinois, have invented a new, original, and ornamental Design for a Handle for Automobile Window Lifter or the Like, of which the following is a specification, reference being had to the accompanying drawing, forming a part thereof.

Fig. 1 is a lateral elevation of a handle

for automobile window lifter or the like, showing my new design; and

Fig. 2 is a front elevation thereof.

I claim:

The ornamental design for a handle for automobile window lifter or the like as shown.

In witness whereof, I hereunto subscribe my name this 5th day of September, 1930.

JOHN STERLING GULLBORG.
